UNITED STATES PATENT OFFICE

HEINRICH JACOB, OF FRIEDENAU, NEAR BERLIN, GERMANY, ASSIGNOR TO THE FIRM
ZEISS JKON AKTIENGESELLSCHAFT GOERZWERK, OF ZEHLENDORF, NEAR BERLIN,
GERMANY

DESIGN FOR A TABLE BAROMETER

Application filed August 31, 1932, Serial No. 44,722, and in Germany May 14, 1932. Term of patent 7 years.

To all whom it may concern:

Be it known that I, HEINRICH JACOB, a citizen of the Republic of Germany, residing at Wilhelmshoherstrasse 16, Friedenau, near Berlin, Germany, have invented a new, original, and ornamental Design for Table Barometers, of which the following is a specification, reference being had to the ac-

companying drawing, forming part thereof. The figure is a perspective of a table barometer, showing my new design. The base portions of the barometer are oval.

I claim:

The ornamental design for a table barometer, as shown and described.

HEINRICH JACOB.
